UNITED STATES PATENT OFFICE.

OTTO FAHRNI, OF THOUNE, SWITZERLAND, ASSIGNOR TO WALTER GERBER, OF THOUNE, HOFSTETTEN, SWITZERLAND, AND ERNST SCHNEIDER, OF BÄCHIMATTE, THOUNE, SWITZERLAND.

AUTOMATIC EMBROIDERING-MACHINE.

1,378,668.

Specification of Letters Patent. Patented May 17, 1921.

Application filed November 17, 1920. Serial No. 424,758.

To all whom it may concern:

Be it known that I, OTTO FAHRNI, a citizen of the Swiss Confederation, and residing at Thoune, Switzerland, have invented certain new and useful Improvements in Automatic Embroidering-Machines, of which the following is a specification.

The subject-matter of the present invention is an automatic embroidering-machine wherein the needle-holders are arranged on slides that are moved to and fro at right-angles to the plane of the frame along a constant path, and members arranged at both sides of the frame for tightening the threads on that side of the frame on which the needles are situated are combined with a device which is influenced in such a manner by a pattern-card controlling the movement of the frame that the distance moved through by the said members when tightening the threads becomes less each stitch corresponding to the amount of thread used.

Preferably, the thread-tightening members are suspended from vertically guided members which are driven by parts that rotate alternately to and fro, the movement of which is diminished at each stitch from a predetermined starting position, corresponding to the amount of thread used, by means of stops adjusted by a feed device.

Conveniently, the thread-tightening members have the form of plates.

Other features of the invention will be described hereinafter and pointed out in the claims.

One embodiment of the invention is illustrated by way of example in the accompanying drawing, wherein:

Figure 1 is a vertical section taken on the line I—I in Fig. 2, and

Fig. 2 is a plan partly broken away showing those parts of one form of machine according to the invention which are necessary for its understanding;

Fig. 3 is a section taken on the line III—III in Fig. 2, and

Fig. 4 is an end elevation showing part of the machine as seen looking in the direction of the arrow IV in Fig. 2;

Fig. 4^a is a side elevation of some of the parts shown in Fig. 4, and

Figs. 5, 6, and 7 are detail views referred to hereinafter.

Like reference numerals designate like parts throughout the several views.

Referring to the drawing, in a machine framework 1, whereof only part is shown, an embroidering-frame 2 is mounted to be horizontally and vertically displaceable in the manner known in automatic shuttle embroidering-machines, and is controlled by a pattern-card 3 by means of a controlling device that is also not illustrated and that may be of any convenient construction.

Two slides 7 and 8, consisting each of two forked end pieces 5 and a beam 6 connecting the same, are guided to move at right-angles to the plane of the embroidering-frame by two horizontal parallel rods 4. For shifting these two slides cams 10 mounted on a horizontal shaft 9 are provided. Two levers 12 and 13 carrying anti-friction rollers 11 bear through the latter on each of these cams 10 at points diametrically opposite one another. The levers 12, 13 of each pair are drawn toward one another by a spring 14; the levers 12 are connected by links 15 with the slide 7, while the levers 13 are pivotally connected directly to the slide 8.

The beam 6 of each slide carries a row of needle-holders 16 that extend laterally beyond the inner longitudinal side thereof, that is the side nearer the frame 2, which holders are arranged in pairs, one exactly opposite another, on the two beams.

Each of these needle-holders 16 comprises a mandrel 17 (Figs. 6 and 7) which has its one end fast on the beam 6, and on which is rotatable a sleeve 18 that has a slot or recess 19 at its end flush with the free end of the mandrel, through which slot projects a plate 20 extending laterally from the mandrel. A needle-abutment 21 is arranged on each sleeve 18 below the plate 20. This abutment or stop 21 is provided in its upper face with a longitudinal channel 21' serving for receiving an embroidering needle 23. By suitably turning the sleeve 18 by means of an arm 22 on its rear end, a needle 23 inserted into the channel 21' between the plate 20 and the abutment 21 can be clamped and released.

In order to prevent the needle turning about its own axis, which is important when employing an automatic single-thread device, the channel 21' has projecting into it 5 a lug 24 which, when the needle is fast in the holder, takes into a transverse recess in the needle.

For simultaneously clamping and releasing the needles of each row of needle-holders, a rod 25 is passed through the arms 22. 10 Each of these rods 25 carries coil springs 26 and collars 27 between the arms 22, and has one end controlled by a tension spring 28, and its other end pivoted to one end of a 15 two-armed lever 29. In Fig. 2, the springs 28 are, for the sake of clearness, shown broken off, but it will be understood that they are connected to the rods 25. The other end of each lever 29 is pivoted each to one 20 end of a rod 30 which carries a block 31 at its other end. Each of these blocks has a lug 32 (Figs. 4 and 4^a) and a horizontal longitudinal slot 33 in which engages a pin 36 mounted on an angle-lever 34 and 35, 25 respectively, when the slide in question is situated in its inner end position.

The angle-lever 35 allotted to the slide 8 is connected by a link 37 with a lever 40 fulcrumed at 38 and arranged to bear against 30 a cam 39. The angle-lever 34 allotted to the slide 7 is connected by a link 41 with the one end of a two-armed lever 42 whose other end bears on the cam 39. This cam thus co-acts with both angle-levers 34 and 35, so 35 that that one of them whose pin 36 is in engagement with the slot 33 of the respective block 31 pulls the latter and the rod 30 connected therewith against the action of the respective spring 28 downward as seen 40 in Fig. 2 and to the left as seen in Fig. 4^a. Consequently, the rod 25 in question is shifted in the opposite direction, whereby all 45 its springs 26 are pressed against the arms 22 bearing against them. These arms 22 are consequently so turned with the needle-holder sleeves 18 that needles inserted into the holders are clamped.

In order that these needles shall remain clamped until the next stitch or change of 50 needle, that is to say during the time when the slide in question slides outward and inward, when the respective pin 36 is not in engagement with the block 31, each block 31 has allotted to it a pawl 43 that is provided with a finger 44 which extends over the same, and behind which the lug 32 lies when the block 31 is actuated by the pin 36 against the action of the spring 28. The finger 44 of the pawl 43 thus holds the block 55 31 in its end position shown at the left-hand of Fig. 2 until the pawl 43 is lifted by a vertically movable pusher 45 or 46.

The pusher 45 has its lower end pivotally connected with the lever 40 by means of a 60 two-armed lever 47 and a link 48, while the

pusher 46 is pivotally connected with the lever 42. Therefore the cam 39 actuates simultaneously the pusher 45 and the angle-lever 35, the pusher 46 and the angle-lever 34. The levers 40 and 42 are moved alternately in such a manner by the cam 39 that the pawl 43 of the inwardly-moved slide is lifted and the respective needle-holders are opened by the action of the spring 28 whereby the needles are released, while at the same 70 time the needle-holders of the other slide are so actuated that the released needles are gripped and held fast.

In order that the embroidery threads shall always be tightened on that side of the frame 80 on which the needles on the outwardly-moved slide are situated, on each side of the frame there is arranged a thread-tightening member in the form of a longitudinal plate 49 and 50, respectively, consisting preferably of a light material, such as aluminum, which is lowered by a device described hereinafter from an upper end position of constant elevation to a lower position corresponding to the amount of thread that is 90 used. The use of plates as thread-tightening members has the advantage that when they rise, the parts of thread situated in front of and behind them cannot become entangled.

Each of the plates 49 and 50 is suspended at its ends on an endless band or tie 51 and 52, respectively, which are respectively guided by two pulleys 53, 54 and 55, 56 arranged one over another. The shaft 57 and 100 60 of the lower pulleys carry near their middle each an intermediate pulley, not shown. That intermediate pulley which is on the shaft 57 of the pulleys 54 is connected by a crossed belt 58 or the like with a pulley 105 59, while that on the shaft 60 of the pulleys 56 is connected by an uncrossed belt 61 or the like with a pulley 62. These pulleys 59 and 62 are freely rotatable on and slideable axially along the shaft 63, which carries 110 between them a toothed wheel 64, with which meshes a pinion 65.

Each of the pulleys 59 and 62 is provided on its inner face with a laterally projecting stop or pin 66 and 67, respectively, while the wheel 64 is provided on each side with four pairs of pins 68 and 69 which are displaced 90° relatively to one another, that is are spaced 90° apart. The inner pins 68 are the same distance from the axis of rotation as are the pins 66 and 67 of the pulleys 59 and 62, so that the pins 66 and 67 can bear against the pins 68, as shown in Fig. 1. The inner pins 68 serve as stops for limiting the angular movement of the pulleys 59 and 62 120 in a counter-clockwise direction. In the opposite, that is in the clockwise direction the pulleys 59 and 62 are moved always into exactly the same position by a jointed rod 70 and 71, respectively, and a cam 72 on 130

the shaft 9, so that the plates 49 and 50 always occupy the same upper end position. When the wheel 64 is rotated stepwise in a clockwise direction, then the pulleys 59 and 62 can turn a corresponding lesser angular distance to the left or counterclockwise, and the plates consequently descend lower until the threads in the needles are finally used up.

10 The purpose of the pins 69 is that each time after new needles have been threaded afresh with threads of a predetermined length, the play between the pins 66 and 67 shall be as large as possible, for which reason the latter must be moved out of reach of the pin 68 in question. This is brought about by means of two coaxial drivers or pins 69 coating with upwardly beveled tongues 73 of two levers 75 that are pulled 20 toward one another by a spring 74 and engage with their free ends in peripheral grooves in the hubs of the pulleys 59 and 62; when the pins 69 bear on the tongues 73 the levers 75 move the pulleys apart. As soon as the pins 69 have moved past the tongues, however, the levers 75 and the pulleys 59 and 62 move together, so that the pins 66 and 67 have their motion limited again by the pins 68 next in order to the 30 left of them as seen in Fig. 1.

Provision is made that the wheel 64 shall be fed forward before each stitch to be made an amount corresponding to the length of the thread used in making the stitch. For 35 this purpose the shaft 76 of the pinion 65 carries a feed mechanism which comprises a ratchet-wheel 78 prevented from moving backward by a catch 77, a feed pawl 80 mounted on a lever 79, and a spring-controlled toothed sector 81 mounted beside the lever 79, on the hub 82 of which sector one end of a tie 83 is wound and attached. The tie 83 is led around two guide pulleys 84 and 85 to a device controlled by the pattern 40 card 3.

This device (Fig. 2) comprises five feeler pins 86 that coat with a corresponding number of rows of holes in the card 3, the upper ends of which pins, when unable to 50 enter a hole in the card, extend above a plate 87, so that levers 88, 89, 90, 91 and 92 mounted to swing about vertical pivots on the plate 87 abut against them. Each of these levers carries a pulley 93 rotatable about a 55 vertical pivot, and the tie 83 is led around these pulleys along a zigzag course as shown in Fig. 2, and attached at its other end to a pin 94 on the plate 87. When the pins 86 enter into holes in the pattern card 3 the 60 allotted levers can rock inward a distance limited by a pin 95 and a lug 96, one of each being allotted to each lever. The length of this distance, and the distance of the pulleys from the fulcrums of their levers is 65 different in each case; for example, when the

lever 88 is actuated the tie 83 moves the sector 81 one tooth, while the lever 89 causes it to move two, the lever 90 four, the lever 91 eight and the lever 92 fifteen teeth. Thus it is seen that the lever 92 causes a movement 70 of the toothed sector 81 that is equal to that caused by all the four levers 88, 89, 90 and 91 together. As the tie 83 is led around all the levers 88, 89, 90, 91, 92 it is obvious that the movements of all these levers are 75 added together in their effect on the tie 83, so that when for example the levers 88, 90 and 91 are released by their allotted feeler pins 86, the sector 81, which a spring 97 tends to rotate counter-clockwise, is shifted 80 $1+4+8=13$ teeth in this direction.

On the side of the sector 81 facing the lever 79 is mounted a pin 98 constituting a stop for the latter. The lever 79 carrying the feed pawl 80 of the wheel 78 can be 85 turned counter-clockwise by a spring 99, that coats with it, only until it abuts against the pin 98. This causes the ratchet-wheel 78 to rotate a like distance in the same direction and by means of the shaft 76 of 90 the pinion 65 shifts the toothed wheel 64, by which the path of the pins 66 and 67 is shortened by 13 units and, consequently, that of the thread-tightening plates 49 and 50 by 95 a like amount. It will thus be seen that by 95 suitably perforating the pattern card 3 the distance moved through by the thread-tightening plates can be regulated.

In order that the tie 83 shall not be 100 stressed injuriously when the lever 79 strikes against the pin 98, the toothed sector 81 is locked by a detent 100 at a convenient moment. The lever 79 is returned into its starting position by a link 101 attached to it, a two-armed lever 102 connected with the 105 latter, and a cam 103 that is carried on the shaft 9 and coats with the lever 102. The toothed sector 81 and the levers 88, 89, 90, 91 and 92 operatively connected therewith are returned into their starting positions by two 110 cams 104 (whereof only one is shown in the drawing; see Figs. 2 and 5) mounted on the shaft 9, pairs of levers 105 that coat with these cams, rods 106 carried by the levers 105, and links 107 that extend through these 115 rods, are pivoted each to one of the levers 88, 89, 90, 91 and 92 and carry outside the rods 106 collars 108 against which the rods 106 bear when the levers 105 rock outward, the levers 88, 89, 90, 91 and 92 being moved 120 with the links. These levers return the toothed sector 81 into its original position by means of the tie 83.

The above described and illustrated embroidery machine comprises only one row 125 of needles, but it is to be understood that several rows arranged one above another could be employed with the same operating mechanism provided that suitable connections were provided. Further, the thread- 130

tightening plates instead of being suspended from endless ties, could be hung on vertically displaceable toothed racks.

I claim:

- 5 1. In an embroidering machine of the class described, the combination with a framework, and an embroidering frame movably mounted therein, of a slide mounted on the framework to move to and fro perpendicularly to said frame, needle-holders carried by said slide, a thread-tightening member mounted in the framework at the same side of said frame as said needle-holders, and means adapted to be controlled by a pattern card and arranged to move said member a shorter distance each stitch corresponding to the consumption of thread, substantially as described.
- 10 2. In an embroidering machine of the class described, the combination with a framework and an embroidering frame movably mounted therein, of a slide mounted on the framework to move to and fro perpendicularly to said frame, needle-holders carried by said slide, guide members mounted to move vertically in said framework, a thread-tightening member suspended from said guide members at the same side of said frame as said needle-holders, and oscillatory feed mechanism adapted to be controlled by a pattern card and arranged to move said guide members a shorter distance each stitch corresponding to the consumption of thread, substantially as described.
- 15 3. In an embroidering machine of the class described, the combination with a framework and an embroidering frame movably mounted therein, of a slide mounted on the framework to move to and fro perpendicularly to said frame, needle-holders carried by said slide, guide members mounted to move vertically in said framework, a thread-tightening member suspended from said guide members at the same side of said frame as said needle-holders, oscillatory feed mechanism comprising stops for vertically reciprocating said guide members and said thread-tightening member, and means adapted to be controlled by a pattern card for coacting with said stops and causing said guide members to move a shorter distance each stitch corresponding to the consumption of thread, substantially as described.
- 20 4. In an embroidering machine of the class described, the combination with a framework, and an embroidering frame movably mounted therein, of a slide mounted on the framework to move to and fro perpendicularly to said frame, needle-holders carried by said slide, a thread-tightening member in the form of a plate carried in the framework at the same side of said frame as said needle-holders, and means adapted to be controlled by a pattern card and ar-

ranged to move said member a shorter distance each stitch corresponding to the consumption of thread, substantially as described.

- 5 5. In an embroidering machine of the class described, the combination with a framework, a shaft journaled therein, and an embroidering frame movably mounted in the framework, of two slides, one at each side of said frame, mounted on the framework to move perpendicularly to said frame, means driven by said shaft for reciprocating said slides, needle-holders carried by each of said slides, two pairs of guide members, one pair at each side of said frame, mounted to move vertically in said framework, two thread-tightening members, one carried by each pair of guide members, arranged to move between the frame and said needle-holders, and oscillatory feed mechanism adapted to be controlled by a pattern card and arranged to move said guide members a shorter distance each stitch corresponding to the consumption of thread, said feed mechanism comprising a wheel, means for rotating the latter step by step, two pulleys operatively connected each with one of said thread-tightening members and arranged coaxially one on each side of said wheel, stops on said pulleys, stops on said wheel arranged to coact with the former stops, means driven by said shaft for turning said pulleys, drivers on said wheel, and means arranged to be actuated by said drivers for moving said pulleys axially away from said wheel during the rotation thereof, substantially as described.
- 10 6. In an embroidering machine of the class described, the combination with a framework, a shaft journaled therein, and an embroidering frame movably mounted in the framework, of two slides, one at each side of said frame, mounted on the framework to move perpendicularly to said frame, means driven by said shaft to reciprocate said slides, needle-holders carried by each of said slides, two pairs of guide members, one pair at each side of said frame, mounted to move vertically in said framework, two thread-tightening members, carried each by one pair of said guide members, arranged to move between said frame and said needle-holders, and oscillatory mechanism arranged to move said guide members a shorter distance each stitch corresponding to the consumption of thread, said mechanism comprising variable pawl-and-ratchet feed mechanism operatively connected with said guide members and actuated by said shaft, and controlling mechanism comprising feeler-pins arranged to coact with a pattern card, a plurality of members movable various distances and controlled by said feeler-pins, and a tie attached to said feed mechanism and operatively connected with

the latter members, substantially as described.

7. In an embroidering machine of the class described, the combination with a framework, a shaft journaled therein, and an embroidering frame movably mounted in the framework, of two slides, one at each side of the frame, mounted on the framework to move perpendicularly to said frame, means driven by said shaft to reciprocate said slides, needle-holders mounted on each of said slides, two pairs of guide members, one pair at each side of said frame, mounted to move vertically in said framework, two thread-tightening members, carried each by one pair of said guide members and arranged to move between said frame and said needle-holders, and oscillatory mechanism arranged to move said guide members a shorter distance each stitch corresponding to the consumption of thread, said mechanism comprising step-by-step feed mechanism that comprises a ratchet-wheel rotatable in only one direction, a pawl actuated by said shaft for feeding said ratchet-wheel, and a regulating member coaxial with said ratchet-wheel and arranged to limit the stroke of said pawl, and controlling mechanism comprising feeler-pins arranged to coact with a pattern card, a plurality of members, each carrying a pulley, arranged to be moved various distances and to be controlled by said feeler-pins, and a tie that is led around said pulleys and has one end attached to said regulating member and its other end attached to said framework, substantially as described.
8. In an embroidering machine of the class described, the combination with a framework, a shaft journaled therein, and an embroidering frame movably mounted in the framework, of two slides, one at each side of said frame, mounted on the framework to move perpendicularly to said frame, means driven by said shaft to reciprocate said slides, needle-holders mounted on each of said slides, two pairs of guide members, one pair at each side of said frame, mounted to move vertically in said framework, two thread-tightening members carried each by one pair of said guide members and arranged to move between said frame and said needle-holders, and oscillatory mechanism arranged to move said guide members a shorter distance each stitch corresponding to the consumption of thread, said mechanism comprising step-by-step mechanism that comprises a ratchet-wheel rotatable in only one direction, a pawl actuated by said shaft for feeding said ratchet-wheel, and a regulating member coaxial with said ratchet-wheel, and arranged to limit the stroke of said pawl, and controlling mechanism comprising feeler pins arranged to coact with a pattern card, a plurality of levers of various lengths arranged to be rocked various distances and to be controlled each by one of said feeler pins, a plurality of pulleys carried each by one of said levers and situated in one plane, a tie that is led zigzag about said pulleys and has one end attached to said regulating member and its other end attached to said framework, and means for returning said levers into their starting position, said latter means comprising a cam fast on said shaft, levers fulcrumed on said framework and arranged to coact with said cam, and links connecting said latter levers each with one of former levers, substantially as described.
9. In an embroidering machine of the class described, the combination with a framework, a shaft journaled therein, and an embroidering frame movably mounted in the framework, of two slides, one at each side of said frame, mounted on the framework to move perpendicularly to said frame, means driven by said shaft to reciprocate said slides, needle-holders mounted on each of said slides, two pairs of guide members, one pair at each side of said frame, mounted to move vertically in said framework, two thread-tightening members carried each by one pair of said guide members and arranged to move between said frame and said needle-holders, and oscillatory mechanism arranged to move said guide members a shorter distance each stitch corresponding to the consumption of thread, said mechanism comprising step-by-step mechanism that comprises a ratchet-wheel rotatable in only one direction, a pawl actuated by said shaft for feeding said ratchet-wheel, and a regulating member coaxial with said ratchet-wheel, and arranged to limit the stroke of said pawl, and controlling mechanism comprising feeler pins arranged to coact with a pattern card, a plurality of levers of various lengths arranged to be rocked various distances and to be controlled each by one of said feeler pins, a plurality of pulleys carried each by one of said levers and situated in one plane, a tie that is led zigzag about said pulleys and has one end attached to said regulating member and its other end attached to said framework, and means for returning said levers into their starting position, said latter means comprising a cam fast on said shaft, levers fulcrumed on said framework and arranged to coact with said cam, and links connecting said latter levers each with one of former levers, substantially as described.
10. In an embroidering machine of the class described, the combination with a framework, and an embroidering frame movably mounted therein, of a slide mounted on the framework to move to and fro perpendicularly to said frame, needle-holders carried by said slide, a thread-tightening member mounted in the framework at the same side of said frame as said needle-holders, and means adapted to be controlled by a pattern card and arranged to move said member a shorter distance each stitch cor-

lengths arranged to be rocked various distances and to be controlled each by one of said feeler pins, a plurality of pulleys carried each by one of said levers and situated in one plane, a tie that is led zigzag about said pulleys and has one end attached to said regulating member and its other end attached to said framework, and means for returning said levers into their starting position.

11. In an embroidering machine of the class described, the combination with a framework, a shaft journaled therein, and an embroidering frame movably mounted in the framework, of two slides, one at each side of said frame, mounted on the framework to move perpendicularly to said frame, means driven by said shaft to reciprocate said slides, needle-holders mounted on each of said slides, two pairs of guide members, one pair at each side of said frame, mounted to move vertically in said framework, two thread-tightening members carried each by one pair of said guide members and arranged to move between said frame and said needle-holders, and oscillatory mechanism arranged to move said guide members a shorter distance each stitch corresponding to the consumption of thread, said mechanism comprising step-by-step mechanism that comprises a ratchet-wheel rotatable in only one direction, a pawl actuated by said shaft for feeding said ratchet-wheel, and a regulating member coaxial with said ratchet-wheel, and arranged to limit the stroke of said pawl, and controlling mechanism comprising feeler pins arranged to coact with a pattern card, a plurality of levers of various lengths arranged to be rocked various distances and to be controlled each by one of said feeler pins, a plurality of pulleys carried each by one of said levers and situated in one plane, a tie that is led zigzag about said pulleys and has one end attached to said regulating member and its other end attached to said framework, and means for returning said levers into their starting position, said latter means comprising a cam fast on said shaft, levers fulcrumed on said framework and arranged to coact with said cam, and links connecting said latter levers each with one of former levers, substantially as described.

12. In an embroidering machine of the class described, the combination with a framework, and an embroidering frame movably mounted therein, of a slide mounted on the framework to move to and fro perpendicularly to said frame, needle-holders carried by said slide, a thread-tightening member mounted in the framework at the same side of said frame as said needle-holders, and means adapted to be controlled by a pattern card and arranged to move said member a shorter distance each stitch cor-

- 6 responding to the consumption of thread, each needle-holder comprising two cylindrical concentric members rotatable one in relation to the other, that are flush one with the other at one end and are provided each with a lateral lug whereof the one lug has a lateral recess for receiving a needle to be clamped by the other lug, substantially as described.
- 10 11. In an embroidering machine of the class described, the combination with a framework, and an embroidering frame movably mounted therein, of a slide mounted on the frame - work to move to and fro 15 perpendicularly to said frame, needle-holders mounted in a row on said slide, a thread-tightening member mounted in the framework at the same side of said frame as said needle-holders between the latter and 20 said frame, and means adapted to be controlled by a pattern card and arranged to move said member a shorter distance each stitch corresponding to the consumption of thread; each needle-holder comprising 25 two cylindrical concentric members whereof one is fixed and the other is rotatable about the same, and both are flush one with the other at one end and are provided at that end each with a lateral lug, 30 in one of which lugs is a recess for receiving a needle to be clamped by the other lug; and a longitudinally slidable rod common to all the needle-holders operatively connected to each rotatable member of said holders, 35 substantially as described.
12. In an embroidering machine of the class described, the combination with a framework, and an embroidering frame movably mounted therein, of a slide mounted 40 on the framework to move to and fro perpendicularly to said frame, needle-holders mounted in a row on said slide, a thread-tightening member mounted in the framework to move vertically between said frame 45 and said needle-holders, and means adapted to be controlled by a pattern card and arranged to move said member a shorter distance each stitch corresponding to the consumption of thread; each needle-holder comprising 50 two cylindrical concentric members whereof one is fixed and the other is rotatable about the same, and each is provided with a lateral lug, in one of which lugs is a recess for receiving a needle to be clamped by the other lug; a longitudinally slidable 55
- rod common to all the needle-holders operatively connected to each rotatable member of said holders and having at its one end a block, a driving shaft, lever mechanism driven by the latter and operatively connected with said slide, lever mechanism driven by said shaft and operatively connected with said block, and means for holding said block in one of its end positions when said slide is in one of its end positions, 60 substantially as described.
13. In an embroidering machine of the class described, the combination with a framework, a shaft journaled therein, and an embroidering frame movably mounted 70 in the framework, of two slides, one at each side of said frame, mounted on the framework to move perpendicularly to said frame, means driven by said shaft to reciprocate said slides, two sets of needle-holders mounted one set in a row on each of said slides, two pairs of guide members, one pair at each side of said frame, mounted to move vertically in said framework, two thread-tightening members carried each by one pair 75 of said guide members arranged to move each between said frame and a row of needle-holders, and oscillatory mechanism arranged to move said guide members a shorter distance each stitch corresponding to the consumption of thread; each needle-holder comprising two cylindrical concentric members whereof one is fixed and the other is rotatable about the same and having lugs adapted to clamp a needle between them; two longitudinally slidable spring-controlled rods 80 common each to all the needle-holders in one of said rows and each operatively connected to each rotatable member of the needle-holders to which it is common, each of said rods 85 having at one end a block, lever mechanisms driven by said shaft and operatively connected each with a block of said rods, pawls arranged to hold the blocks in one of their end positions, and means operatively connecting the latter lever mechanisms for actuating the blocks each with the pawl allotted to the other block respectively, substantially as described.
- 90 In testimony whereof I affix my signature 105 in presence of two witnesses.
